UNITED STATES PATENT OFFICE.

THOMAS VICARS AND EDWARD LYNTON VICARS, OF EARLESTOWN, ENGLAND.

BISCUIT OR LIKE EMBOSSED AND CUTTING MACHINE.

Application filed January 5, 1921. Serial No. 435,264.

(GRANTED UNDER THE PROVISIONS OF THE ACT OF MARCH 3, 1921, 41 STAT. L., 1313.)

To all whom it may concern:

Be it known that we, THOMAS VICARS and EDWARD LYNTON VICARS, subjects of the King of England, and residing at Earles-
town, in the county of Lancaster, England, have invented Improvements in or Connected with Biscuit or like Embossing and Cutting Machines (for which we have filed an application in England June 30, 1919, Patent No. 154,850), of which the following is a specification.

This invention has reference to biscuit or like cutting or embossing machines, and more particularly to cutting tables of such machines, as shown in our co-pending application, filed December 22, 1920, Serial Number 432,588, wherein the upper part of the table is adapted to be raised or lowered so as to take different inclinations longitudinally for changing the relation of the table to the cutting and embossing elements, and the invention has primarily for its object to provide improvements in connection with such tables whereby they are rendered generally more serviceable and convenient in connection with the work that has to be performed, in such machines, and so that all the conditions and requirements of the operations which are to be performed can be met and advantageously effected.

The present invention comprises means whereby the upper part of the table is adapted not only to be raised or lowered so as to take different inclinations, longitudinally, but also transversely, that is, by the means employed the table may be raised and lowered bodily, or one end raised or lowered, or the other raised and lowered; and also it can be adjusted so as to take different inclinations transversely; the means employed for these adjustments being separate.

The means for the different adjustments referred to are illustrated in the annexed drawings, and are hereinafter described in connection with them, whilst the features claimed as novel in respect of the invention, are specified or set out in the several claiming clauses concluding the specification.

In the drawings, Figure 1 is a front elevation, Figure 2 a plan, and Figure 3 a cross section of the table showing the various adjusting means.

With regard to the means by which the

table may be adjusted, namely, raised or lowered bodily, or one or other end raised or lowered, or both raised or lowered, this consists of screw gears in each end of the table, operated by two sets of hand operated gears—preferably concentric—and so arranged and adapted that they may be thrown into engagement with each other, or put out of engagement; and when in engagement, so that the parts are worked together, by rotating them the screw gears at each end will be worked simultaneously, so that the table will be bodily raised or lowered. On the other hand, when they are disengaged from one another, one or other of the screw gears at the opposite ends of the table will or may be operated by rotating one or other parts of the hand operating gear.

With regard to the screw gear, this consists in the case shown of threaded studs 1, in the base 2 of the table, on the upper rounded ends of which the upper part 3 of the table rests, a pair of such studs being employed at each end; and they are prevented from rotating by square or like heads 6 on their lower ends fitting in corresponding square or like holes in the bottom of the bed portion 2; but free to be screwed up and down. This screw up and down is effected by screw gear wheels 4, the bosses 5 of which are internally threaded, with which threads, the threads of the studs 1 mesh.

The pairs of tooth worm wheels 4 at each end mesh with each other, and they are driven by the worms 9 and 10 on the concentric hollow and solid shafts 11 and 12, respectively; 10 meshing with the wheels 4 at the further end of the table, and 9 meshing with those of the wheels 4 on the nearer end of the table.

The upper rounded ends of the studs 1 fit into cup shaped recesses in the under-surface of the upper portion 3 of the table.

The base 2 of the table has curved trunnions or journals 13 being sections of a cylinder, which fit and rest in two corresponding curved seats or bearings in the framing 100 of the machine—not shown—the center of the curves of which lie in or about, or near the surfaces 15 of the table.

The adjustment of the table about this center is effected by means of an internally threaded nut or small hand wheel 16 work-

ing on a threaded rod 17, mounted on a suitable part of the embossing machine, the wheel 6 acting upon a lever 18 fixed on to one of the upper surfaces of the trunnions 5 portion 13 by screw studs 19. Thus by screwing the hand wheel 16 up or down the threaded shaft or rod 17, the table can be adjusted transversely, that is rocked about the supports or bearings in which the trunnions 13 rest, the movement being limited at the stops 20.

In the case shown the rod 17 is secured to a shaft 21 which may be a shaft of the machine.

15 The means of operating the gear wheels 9, 10 and their shafts 11 and 12, consist of two hand wheels 22, 23, on the shafts 11 and 12 respectively, the hubs of which constitute a clutch, one having pins or dowels 24, and 20 the other having holes 25 into which the pins or dowels may pass; and one of these wheels, say 23, may be moved longitudinally away from or up to the other by a screw gear consisting of an internally threaded cap 25 nut 26 mounted on the reduced end of the spindle 12 as shown, the internal thread of which meshes with the externally threaded projecting boss 28 of the wheel 23, which is adapted to slide on a feather or key on the 30 shaft 12.

Thus by turning this nut 26, the wheel 23 will be moved away from 22, and the dowels 24 will be moved out of the holes or recesses 25, so that the two wheels are disengaged, 25 and the two different gear wheels 9 and 10 connected with their separate sets of wheels 4 and studs 1 can be separately and differently adjusted, so as to adjust the table as regards its inclination or level, in the longitudinal direction to any angle required.

40 Then by operating the cap 26 in the opposite direction, so as to move the wheel 23 into engagement with 22, the two gear wheels 9 and 10, and the other gears which they operate, will be worked simultaneously, and the adjustment bodily of the table up or down can be effected.

Thus by the gear mechanism described, the different species of adjustment specified are capable of accomplishment.

50 What is claimed is:—

1. In a biscuit or like cutting or embossing machine table adjusting means having screw means at different parts of it adapted to be actuated together or separately at the 55 different ends, at will, in combination with means for adjusting the table circularly about its longitudinal axis; substantially as set forth.

2. A biscuit cutting and embossing machine, including a cutting table composed of 60 a base portion and an upper portion for receiving the biscuits to be cut, means for adjusting the base portion on its longitudinal axis, and means for raising or lowering the 65 upper portion relative to the base and for adjusting said upper portion on its transverse axis.

3. A biscuit cutting and embossing machine, including a cutting table composed of 70 a base portion and an upper portion for receiving the biscuits to be cut, means for adjusting the base portion about its longitudinal axis, and means carried by the base portion for adjusting the upper portion, including a pair of intermeshing gears rotatably mounted in the base at each end thereof, having rods extending axially therethrough to engage the upper portion, said rods being in screw-threaded engagement with said 75 gears and being held against rotation, and means adapted for operating each pair of gears independent of the other pair for adjusting the upper portion on its transverse axis or interengaged and operated together 80 for raising or lowering the upper portion.

85 In testimony whereof we have signed our names to this specification in the presence of two subscribing witnesses.

THOMAS VICARS.
E. LYNTON VICARS.
